Attorney.

UNITED STATES PATENT OFFICE

AUGUSTUS MURRAY BOWZER, OF LYNN, MASSACHUSETTS

PRINTER'S QUOIN

Application filed November 21, 1927. Serial No. 234,727.

The invention relates to what is known in the printers' trade as a printer's quoin for securing a type form rigidly in position in a printer's chase preparatory to being used in a printing press. The invention consists of a printer's quoin having a suitable body with a clamping member therein which has an outward and downward movement which not only forces the type together in a horizontal plane, but also forces them downwardly against a hard smooth plate so the type will be laid evenly and in a symmetrical manner to prevent workups. The invention further consists of special details of construction and will be taken up in detail in the specification and claims.

The object of the invention is to provide a printer's quoin having a clamping member with an outward and downward movement to force the type together and force them downwardly, and at the same time have the various moving parts in relation to each other and to the frame that they cannot be removed or misplaced thereby making a printer's quoin a complete unit in construction, which is simple in construction, strong and durable, cannot get out of adjustment and cheap to manufacture.

Referring to the figures, Fig. 1 is a plan view of a printer's chase with a printer's type form and furniture located in such relation to the chase that the type form can be securely fastened in position by the improved printer's quoin, having one or many clamping members. Figure 2 is a front elevation showing the clamping member of the quoin. Figure 3 is a rear elevation of the quoin. Figure 4 is a plan view parts broken away and others in section. Figure 5 is an end view. Figure 6 is a cross section of the main body showing the slot in the clamp support and the screw in the slot for limiting the movement of the clamping member. Figure 7 is a cross section through the body and the clamp showing the operating screw and the inclined slot. Figure 8 is a cross section taken in the same place as Figure 7, except that the clamping member is in its outward position. Figure 9 is an enlarged

detail showing a ledge to prevent the screw from being removed.

Referring to the drawings, 10 represents the body support of a printer's quoin having a suitable clamping member which is used for clamping the type form 11 rigidly in position to the chase 12. The varying sizes of type forms require clamping furniture 13 to be used to build up as an abutment against which the clamping members operate for rigidly securing the type form in position.

Printers' quoins are used on two sides of the type form, as shown in Figure 1 which has the furniture 13 so arranged that when the clamping quoins are brought into operation the furniture is set into position in such a way that when pressure is brought to bear against the chase in the furniture they will pass each other at right angles. This allows the pressure exerted to take place on all four sides, thereby clamping the form rigidly to the chase.

Single or double quoins can be used as desired but as the invention directly relates to the quoin itself the description of one would be sufficient.

The body of the quoin 10 is provided with an inclined longitudinal slot 14 adapted to receive the adjustable sliding clamp, having a clamping member 15 and a supporting member 16. The lower part of the body 10 is cut away forming two supporting members 17 and 18 which lessens the friction surface of the quoin body on the table in which the type form is set up and allows the movable parts to be assembled. The supporting member 16 of the clamp is formed at a suitable angle to the clamping member 15 which allows the said clamp 15 when it moves outwardly to also move downwardly. These resulting movements exert an outward and downward movement against the printing forms which would otherwise cause the form and the furniture to buckle if the clamp 16 moved outwardly in a straight line. The form 11 and the furniture 13 is clamped rigidly in position in an even manner by a continued upward and downward movement of the clamp 15, so that they will not only be pressed together, but will be forced down-

wardly in an even manner on the table on which they are built up.

Centrally disposed and formed in the inclined supporting member 16 is a semi-circular and conical inclined depression 19 which cooperates with the screw 20 for forcing the clamping members 15 and 16 outwardly and downwardly for clamping purposes.

10 The screw 20 is provided with a ball end 21 which conforms to the depression 19. The screw 20 is also provided with a socket 22 in which is inserted a hand key 23 for turning the screw 20 for moving the screw up or down in accordance with the direction of rotation to operate the clamping member. The screw 20, after it is placed in position in the body supporting member 10 cannot be removed or lost for it is prevented from being taken out of position by the ledge 24 as shown in Fig. 9.

15 The supporting member 16 is held in position and prevented from sliding out of the incline 14 by a slot 25 formed in the clamping supporting member and is limited in its movements by a screw 26 threaded into the frame 10 and extending into the slot 25 which permits the clamping member to move back and forth limited only by the length of the 20 slot 25.

25 It will be noted that the inclined slots 14 in the body 10 in which the clamping supporting member 16 slides and the inclined conical depression 19 are opposed to each other which allows the clamping member to be held rigidly in position at all times after the clamp is set in position. The downward movement of the screw 20 in the conical depression 19 causes the clamping supporting 30 member 16 to be forced downwardly in the guide slot 14 thereby keeping the clamp rigidly in position against the furniture and type form and preventing them from getting out of true. Even though the ways may be 35 worn or a little loose, the action of the screw 20 in the conical depression 19 will force the clamping support 16 rigidly against the lower surface of the slot 14 and with the opposed inclined construction causing a perfectly rigid construction at all times, which 40 is important in a device of this kind.

45 In operation the type form 11 is placed on a smooth table with the furniture 13 inside the chase 12 and it becomes necessary to hold the type form evenly in position. It is well known in the art that type to be used in printing presses must be very even and of a standard height so that the type will print evenly while running through a printing 50 press. It is one of the chief difficulties in the printing trade to place type evenly in position and to hold it there and it is also difficult not to cause the type form and the furniture to buckle up or get out of true while 55 they are being secured in position. To avoid

any misplacement of the type while being set up, I have provided this improved quoin which when forced into clamping relation to the furniture 13 forces the said furniture against the type form inwardly and downwardly which causes the type and the furniture to be forced against the smooth table and held securely in position in an even manner having all the type in a registering position. The inward and downward movement is caused by placing the key in the socket 22, of the screw 20 and turning it around. This turning movement causes the screw to move downwardly and the ball end of the screw 20 wipes down the inclined surface 19 thereby forcing the supporting member 16 and clamping plate 15 outwardly and downwardly in the slot 14 which causes the furniture 13 to clamp the type form in position. One of the chief troubles in a quoin 60 is to prevent the various parts from being taken out and lost. To avoid this a ledge 24 is made on the body 10 which prevents the screw 20 from being taken out and mislaid. The screw 20 when assembled is threaded in from underneath, between the supporting members 17 and 18 opened. The clamping supporting member 16 is put in position in the incline 14 and limited in its movements by the slot 25 and screw 26. This limiting 65 movement of the clamping member prevents the screw 20 from being taken out. As shown in Figure 8, the clamping members 15 and 16 are in their outward position and the edge of the inclined slot is directly under the screw 20. By this construction the screw 20 is prevented from being taken out through the frame 10 by the ledge 24, and is prevented from being taken out from the under side by the clamping supporting member 16, thereby making the quoin support and operating parts of unit formation with no parts 70 to be lost or no occasion for removing the various members which prevents any losing or misplacement of any of the parts.

75 In accordance with the provisions of the patent statutes, I have described the principle of operation of my invention, together with the apparatus which I now consider to represent the best embodiment thereof, but I desire to have it understood that the apparatus shown is only illustrative and that the 80 invention can be carried out by other means.

85 What I claim as new and desire to secure by Letters Patent of the United States is:

90 1. A printer's quoin having a main body, a sliding clamping member, an inclined slot in the body, an inclined support integral with the clamping member for moving the said clamping member outwardly and downwardly.

95 2. A printer's quoin having a main body, a sliding clamping member, an inclined slot in the body, an inclined support integral with the clamping member, a screw threaded

into the body and operated by a key, and means in relation to the screw for forcing the clamping member outwardly and downwardly.

6 3. A printer's quoin having a main body, a sliding clamping member, an inclined slot in the body, an inclined support integral with the clamping member, a screw threaded into the body and operated by a key and opposite 10 the inclined slot in the supporting member for forcing the clamping member outwardly and downwardly.

4. A printer's quoin having a main body, a sliding clamping member, an inclined slot in the body, an inclined support integral with 15 the clamping member, a screw threaded into the body and operated by a key and means for tightening the supporting member in the inclined slot for holding the moving parts in 20 relation to the body.

5. A printer's quoin having a main body, a sliding clamping member, an inclined slot in the body, an inclined support integral with the clamping member, a screw threaded into 25 the body and operated by a key, an oppositely inclined slot in the supporting member co-operating with the screw for holding the inclined support in tightened relation to the inclined slot for holding the moving parts in 30 relation to the body.

6. A printer's quoin having a main body, a sliding clamping member in the body, an inclined slot in the body, an inclined support integral with the clamping member, a screw 35 threaded into the body and operated by a key, and means for holding the moving parts from being removed or misplaced.

7. A printer's quoin having a main body, a sliding clamping member in the body, an inclined slot in the body, an inclined support integral with the clamping member, a screw 40 threaded into the body and operated by a key, a ledge integral with the body to prevent the screw from being taken out, a slot in the sliding support, a screw threaded into the main body and extending into the slot both to limit the outward movement of the clamping member and preventing both the clamping member and the operating screw from being 45 removed.

8. A printer's quoin having a main body, two supports on the under side of the body, slots cut in the body and in the supports, an inclined support integral with the clamping 50 member and located in the slots, a screw threaded into the body and operated by means of a key for providing a minimum surface support and for allowing the screw to be assembled.

60 AUGUSTUS MURRAY BOWZER.
